AUTOMATIC IGNITER

Scott V. E. Taylor, Zanesville, Ohio

Application March 25, 1950, Serial No. 151,881

12 Claims. (Cl. 67—10.1)

1

This invention relates to igniters and more particularly to one for automatically igniting the fuel in a smudge pot or similar article.

One of the objects of the invention is to produce an improved igniter which will be automatically operated when certain conditions occur.

A further and more specific object is to produce an igniter for a smudge pot which will be so controlled by a thermostatic element that the igniter will be automatically operated when the air temperature drops below a predetermined reading.

Another object is to produce an igniter which can be pre-set for operation and then automatically operated when certain conditions occur.

Yet another and more specific object is to produce a smudge pot igniter of the thermostatic control type which will be simple in construction, economical to manufacture, easily attached to smudge pots and reliable in operation.

A still further object is to produce a smudge pot igniter which will be so constructed that quick and dependable ignition will occur when a predetermined temperature is reached at which ignition is desired.

A further object is to provide improved means for releasing a spring biased member by a thermostat.

Other objects of the invention will become apparent from the following description taken in connection with the accompanying drawings showing a preferred construction.

In the drawing:

Figure 1 is a side view of a smudge pot having mounted thereon an improved automatically operated igniter embodying the invention;

Figure 2 is a top view of the igniter;

Figure 3 is an enlarged view showing the igniter mounted on the smudge pot with parts being shown broken away and in section, the sectional view of the igniter being taken on the line 3—3 of Figure 2;

Figure 4 is a side view of the igniter with parts being broken away and in section to show structure within the housing;

Figure 5 is a cross sectional view showing the igniting wheel and flint, said view being taken on the line 5—5 of Figure 4;

Figure 6 is a sectional view taken on the line 6—6 of Figure 4 showing details of the attaching of the thermostatic element to the housing; and

Figure 7 is an enlarged sectional view taken on the line 7—7 of Figure 2 showing the main wick saturating system.

Referring to the drawings in detail, S indicates a well known smudge pot for use in orchards whereby, when lighted, a smudge will be produced in the area and thereby prevent damage to the trees, due to temperatures within a limited range

2

just below freezing. The smudge or fog produced will lie adjacent the ground and so surround the trees that temperatures, say in the range between 28 to 32 degrees F., present under normal atmospheric conditions will not be present in the smudge area. In order to produce the necessary smudge in the atmosphere to prevent damage from freezing, a large number of pots must be employed and of course this presents a problem in lighting all these pots at a proper time to prevent damage, particularly where a temperature fall to a point below freezing may be very rapid and unexpected. Smudge pot lighting presents a considerable problem when it has to be done by an individual going to each pot, because the freezing temperatures which occur generally come during the night, thus requiring lighting under adverse conditions, particularly as to visibility.

20 Numerous igniting devices have been attempted to be produced which will permit the automatic igniting of smudge pots whenever a temperature reaches a predetermined value, but these igniting devices have not been successful because of numerous reasons, possibly the most important of which is the failure of the igniter to operate when operation is required. When thermostatic elements are employed to control the operation of the igniters, the structure employed to be controlled has been such that the thermostatic element is erratic with respect to the temperatures at which it is supposed to operate. Often the thermostatic element will not cause the igniter to function at all until a much lower temperature is reached than that at which it should have operated and was so set.

25 With my improved automatically operated igniter, it is believed that all these objections to prior constructions have been overcome and an igniter has been produced which will operate efficiently and accurately, with a very minimum number of failures in lighting the smudge pots. This improved igniter is shown as being mounted on a smudge pot in Figure 1 and is generally indicated by the letter I.

30 As best shown in Figures 2, 3 and 4, the igniter, in its preferred construction, has an elongated casing C made from two pressed metal parts 10 and 11. The main part 10 of the casing is of inverted U-shaped construction so as to be open at the bottom. The other part 11 is in the form of a plate having flange ends and is so constructed that it can act as a bottom for the U-shaped part 10 and also provide necessary mounting structure for the rotatable parts of the igniter. Flange 12, at the rear end of the casing part 11, forms an end wall for the U-shaped part and also provides means for attaching the two parts together as by a screw 13. The other front flange 14 of the part 11

extends upwardly into the U-shaped part 10 inwardly of its end wall 15. The front end on the two casing parts may be attached in any suitable manner, as by the pin 14' shown.

Flanges 12 and 14 of the casing part 11 have journaled therein a shaft 16 with the rear end extending outwardly beyond the casing and the forward end extending into the space between the forward flange 14 and the end wall 15. The shaft is held in flange 14 by a shoulder on one side and a washer and pin arrangement 16' as shown. Mounted on this forward end of the shaft 16 is a knurled wheel 17 which is arranged to move over the end surface of a flint 18 to thereby produce sparks in a well known manner. The flint is mounted in a member 19 secured to the flange 14 and overlying the knurled wheel. In order that the flint may be maintained in pressure engagement at all times with the knurled surface of the wheel 17, a leaf spring 20 is secured to the top wall of the U-shaped casing part 10 with its free end acting on the end of the flint which is opposite the end engaged by the knurled wheel.

The shaft 16 is arranged to be rotated by means of a spring which is shown as an elongated coil spring 21 surrounding the shaft 16 throughout substantially its length between the two flanges 12 and 14 of the casing part 11. The forward end of the spring is secured to the forward flange 14 and the rear end of the spring is secured to the shaft, as by a pin 22. The extreme rear end of the shaft which extends out beyond the rear end of the casing is provided with a key type handle 23. Inwardly of this handle is a ratchet wheel 24 which is arranged to be engaged by a latch means 25. The element forming the latch means is made from leaf spring material and is mounted in a support member 26 welded to the part 11 of the casing. The latch element is secured to the mounting member 26 by being positioned in a slot in said part and held in said slot by a pin 27. The latch means is so mounted in the mounting member that its upper end will be normally out of engagement with any of the teeth on the ratchet wheel, and to engage the latch means with a tooth of the ratchet wheel it is necessary to flex the leaf spring structure so it will be somewhat bowed. The resiliency of the leaf spring structure of the latch means is such that unless the latch means is maintained in engagement with a tooth by external forces, it will spring back to its normal condition free of engagement with any of the teeth of the ratchet wheel and thereby permit the shaft 16 to freely rotate, all notwithstanding that the shaft may be acted upon with considerable torque by a wound up condition of the coil spring 21 when the latch means is engaged.

The particular means which is employed for maintaining the latch means engaged with a tooth of the ratchet wheel to thereby hold the spring 21 in a wound up condition and for controlling the release of the latch means comprises a wire 28, a swingable member 29 and a thermostatic element 30. The wire 28 is connected to the latch means 25 and extends from there around the rear edge of one side wall of the casing to the front end of the casing adjacent the knurled wheel which performs the sparking. The wire is then secured to the front end of the casing by a screw 31. This wire is normally in such a slack condition that it will permit the latch means 25 to assume its normal position, where it is disengaged from any tooth. If the wire, however,

extends upwardly into the U-shaped part 10 inwardly of its end wall 15. The front end on the two casing parts may be attached in any suitable manner, as by the pin 14' shown.

has its intermediate part moved away from the casing a predetermined distance, it can be caused to hold the latch means 25 in engagement with a tooth of the ratchet wheel. In order to hold this wire outwardly in such a holding position for the latch means, there is provided the swingable member 29 which is shown as being in the form of a small hinge. One part 32 of the hinge will be secured to the side of the casing and the other part 33 of the hinge will be free to swing outwardly and engage the wire and, by its edge, move its intermediate portion to such a position that holding the latch means can be accomplished. The length of the wire will be so selected that the wire can hold the latch means 25 in engaged position with a tooth whenever the hinged part 33 of the swingable means is moved outwardly from the plane of the side of the casing approximately 75 degrees.

To hold this hinge part 33 outwardly, the thermostatic element 30 is employed which is a bowed member made from strips of metal having different coefficients of expansion, as is well known. One end of this thermostatic element is secured to the side of the casing opposite the swingable member by means of screws 34. From this mounting position the element is arranged to bow over the top of the casing and down to a point adjacent the top of the hinge part 33 of the swingable member 29. This free end of the element is provided with a notch 35 which can receive the top marginal portion of the hinged part and thus hold it in its outward position where it can maintain the wire taut and the latch means 25 engaged with the tooth. Since the wire, under a taut condition, will tend to force the thermostatic element laterally and affect its accuracy, such can be prevented by the use of the guide strip 36. It will be noted that this guide strip is secured to the top surface of the casing C by screws 37 and projects outwardly to act as a guide and abutment for that side of the free end of the thermostatic element towards which the element will be twisted by the action of the taut wire. The thermostatic element is mounted to be in a plane less than 90 degrees to the longitudinal axis of the casing and this is accomplished by deforming outwardly a portion of the side of the casing to which the element is secured by the screws 34, all as best shown in detail in Figure 6. The guide member 36 will also have the same angular position as the thermostatic element.

The thermostatic element is so constructed that the free end of the element will move outwardly away from the casing as the temperature drops and the design is such that when the temperature surrounding the igniter approaches the freezing temperature, the free end will be so moved outwardly as to release the hinge part 33. Due to the angular position of this part and the forces acting on it by the taut wire 28, the hinge part will collapse, when released, against the side of the casing and thus permit the wire to be slack. The resilient action of the latch means will then cause it to become disengaged from the engaged tooth of the ratchet wheel and consequently the coil spring 21 surrounding the shaft 16 will give said shaft a rapid rotation, which rotation will result in the knurled wheel producing sparks by being moved over the end of the flint.

Whenever the knurled wheel and the flint causes sparking, a wick 38 will be ignited and by means of this wick the fuel in the smudge pot lighted. By reference to Figures 3 and 5 it will be

seen that this wick is positioned in a tube 39 which extends from the casing C at a point closely adjacent one edge of the knurled wheel, into the smudge pot through its cover 40. The wick may be of any suitable inflammable material or can be a fuse. As shown, it is of suitable inflammable material and is arranged to be maintained saturated with a readily inflammable liquid such as ordinary cigaret fluid lighter, gasoline or the like. To accomplish this the tube adjacent the igniter will be provided with a small annular member 41 suitably brazed or otherwise secured to the top of the tube 39 and thereby provide a chamber 42 in which the inflammable liquid can be placed. Extending upwardly into the chamber and above the liquid line is a small conduit 43 which is arranged to be in communication with the interior of the wick carrying tube 39. To conduct the liquid from the chamber 42 to the wick 38 in the tube 39 to cause it to be fully saturated and readily inflammable, there is provided a secondary wick 44 which can be tied to the main wick 38 and then extend upwardly through the conduit 43 and into the liquid in the chamber 42. The tube 41 forming the chamber 42 can be closed by a cork 45 or any other capping means.

In order that the igniter may be readily attached to a smudge pot already in use and not having an igniter or by a manufacturer to a newly constructed pot, the casing has two attaching brackets 46 and 47 extending laterally in the same direction as the tube. In the ends of these brackets are holes 48 whereby screws 49 may be employed to attach the brackets to the smudge pot cover 40. The brackets will be of sufficient length that the igniter will set some distance to one side of the pot, so that when the pot is lighted and operating to produce a smudge, the igniter will not be damaged by heat.

In operation of my improved igniter, the igniter is installed on the smudge pot, as shown, with the main wick 38 caused to be saturated with an inflammable liquid, which is accomplished by filling the chamber 42 so that the small wick will conduct this liquid to the main wick. To set the igniter for operation, the hinge part 33 is swung outwardly and the thermostatic element 30 caused to receive such part in the slot 35. This will pull on the wire 28 and bow the latch means 25 so that it engages the ratchet wheel. The shaft 16 is now turned by hand to wind up coil spring 24 where it will be held by the latch means. If desired, the shaft and spring can be wound up prior to setting the hinge part 33. In this way it will not be necessary to "ratchet" the wheel 24 over the latch means.

With the igniter now set, it will automatically operate when the temperature falls to approximately freezing. When such a temperature occurs, the free end of the thermostatic element will be so swung outwardly as to release the hinge part 33 which will then be collapsed against the side of the casing due to its angular position and relation to the force applied by the taut wire. The wire is now permitted to become slack and the latch means will be released by its "springing back" to normal condition. The shaft 16 is now freed for rotation by the wound up condition of spring 24. This causes rapid rotation of the knurled wheel with resulting sparks from the flint and the igniting of the wick. The burning of the wick will then cause the smudge pot fuel to be lighted.

It will be noted that the thermostatic element is so constructed and associated with the control

parts that it does not have to move under any high friction. It thus will have an accurate movement. The angle of the hinge part is such that the taut wire will produce only a small force acting in a direction to push the free end of the thermostatic element against the guide strip 36. Once the wire is permitted to become slack, the latch means will release instantly, due to the inherent strong forces tending to bring it to normal condition from its flexed holding position. The sparking structure, including the knurled wheel and flint, are fully protected against wind and rain.

From an understanding of the structure embodying my invention, it is believed to be obvious that modifications can be made. Other types of igniting wheels can be employed, as well as igniting substances, such as, for example, friction substance and ordinary matches. In view of these obvious modifications, it is therefore understood that I do not intend that the scope of my invention be limited in any manner except in accordance with the appended claims.

What is claimed is:

1. In an igniter, a member rotatable by spring means to accomplish igniting, ratchet means including a latch means associated with the member for holding the member from rotation by the spring means, said latch means being normally biased to a non-holding position, and means for maintaining the latch means in holding position as long as the temperature surrounding the igniter is above a predetermined degree and for automatically allowing it to assume non-holding position when the temperature falls below the said predetermined degree.
2. In an igniter, a member rotatable by spring means to accomplish igniting, ratchet means including a latch means associated with the member for holding the member from rotation by the spring means, said latch means being normally conditioned in a non-holding position, and means for maintaining the latch means in holding position, and means for automatically causing the latch means to assume non-holding position when the temperature falls below a predetermined degree.
3. In an automatically operable smudge pot igniter, a member rotatable by spring means to accomplish igniting, ratchet means including latch means associated with the member for holding the member from rotation by the spring means, said latch means being normally biased to a non-holding position, and means for maintaining the latch means in holding position as long as the temperature surrounding the igniter is above a predetermined degree and for automatically allowing it to assume non-holding position when the temperature falls below said predetermined degree, said last named means comprising a member movable to a position to hold the latch means operable, and a thermostatic element engageable with the movable member only when the temperature is above a predetermined degree.
4. In an igniter having a member rotatable by spring means to accomplish igniting and latch means to hold the member from rotation by the spring means when in biased condition to cause rotation, a flexible cord connected to the latch means and capable of holding the latch means operative when tensioned, and thermostatically controlled means for releasing the cord from its tensioned latch holding condition when a predetermined temperature occurs.
5. In an igniter having a member rotatable by spring means to accomplish igniting and latch

75

means to hold the member from rotation by the spring means when in biased condition to cause rotation, a flexible cord connected to the latch means and capable of holding the latch means operative when tensioned, a movable member to accomplish the tensioning, and a thermostatic element for holding the movable member in tensioning position as long as the surrounding temperature is above a predetermined degree.

6. In an igniter, a rotatable member for accomplishing igniting, spring means for rotating said member, latch means for holding said member from rotation by the spring means, and means for releasing the latch means comprising a thermostatic element, a swingable member, and an anchored flexible cord connected to the latch, said swingable member cooperating with the cord to hold it tensioned and the latch engaged and said thermostatic element holding the swingable member in its latch holding position but releaseable therefrom when subject to a predetermined temperature.

7. In an igniter, a rotatable member for accomplishing igniting, spring means for rotating said member, latch means for holding said member from rotation by the spring means, and means for releasing the latch means comprising a thermostatic element, a swingable member, and an anchored flexible cord connected to the latch, said swingable member cooperating with the cord between its anchor and the latch means to hold it tensioned by a lateral deflection thereof and thereby hold the latch engaged and said thermostatic element holding the swingable member in its latch holding position but releaseable therefrom when subject to a predetermined temperature.

8. In an igniter, a support structure, a rotatable member for accomplishing igniting, a shaft connected thereto and journaled in the support structure, a ratchet wheel carried by the shaft and spaced from the rotatable member, a coiled spring surrounding the shaft between the member and ratchet wheel and having one end connected to the shaft and the other end secured to the support structure, a spring biased latch means for engagement with the wheel to hold the shaft and spring in a wound condition, a cord connected to the latch means at one end and anchored at its other end, and thermostatically responsive means for holding the cord so tensioned that the latch means is engaged with the wheel and for releasing the cord to permit release of the latch means when a predetermined temperature occurs.

9. In an igniter, a support structure, a rotatable member for accomplishing igniting, a shaft connected thereto and journaled in the support structure, a ratchet wheel carried by the shaft and spaced from the rotatable member, a coiled spring surrounding the shaft between the member and ratchet wheel and having one end connected to the shaft and the other end secured to the support structure, a spring biased latch means for engagement with the wheel to hold the shaft and spring in a wound condition, a cord connected to the latch means at one end and anchored at its other end, and means for holding the cord so tensioned that the latch is engaged with the wheel and for releasing the cord to permit release of the latch when a predetermined temperature occurs, said last named means comprising a member movable to a position to

flex the cord to a position to thereby move the latch means to holding position, and a thermostatic element to hold the said member in latch holding position and capable of releasing same when a predetermined temperature occurs.

10. In an igniter, an elongated support structure, a spring operated rotatable member to accomplish igniting mounted in the support structure, means comprising latch means at one end of the structure to hold the rotatable member from rotation by the spring, a cord connected at one end to the latch means and at its other end to the remote end of the support structure, said cord having a slack condition in which the latch means can be in non-holding condition, a swingable member mounted on the intermediate portion of the support structure and capable of swinging outwardly against the cord and thereby pulling the cord taut and maintaining the latch in holding position, and thermostatically controlled means for holding the swingable member in its outward position and capable of releasing it when a predetermined temperature occurs.

11. In an igniter, an elongated support structure, a spring operated rotatable member to accomplish igniting mounted in the support structure, means comprising latch means at one end of the structure to hold the rotatable member from rotation by the spring, a cord connected at one end to the latch means and at its other end to the remote end of the support structure, said cord having a slack condition in which the latch means can be in non-holding condition, a swingable member mounted on the intermediate portion of the support structure and capable of swinging outwardly to an angle less than 90 degrees with the longitudinal axis of the support structure and against the cord to thereby pull the cord taut and maintain the latch in holding position, a bowed thermostatic element for engaging and holding the swingable member in its outward position but capable of releasing it when a predetermined temperature occurs, and a support guide for the thermostatic element preventing its deflection by the tension of the cord acting through the swingable member and tending to collapse it inwardly.

12. In an igniter for smudge pots, an elongated U-shaped casing structure, a shaft mounted lengthwise therein, a knurled wheel mounted at one end of the shaft, a flint for engagement by the wheel to produce sparks, a leaf spring mounted in the casing and acting on the flint to bias it into engagement with the wheel, a coiled spring in surrounding relation to the shaft for rotating the same when wound up, ratchet means including a ratchet wheel on the shaft for holding the shaft from rotation, a handle carried by the shaft for winding up the spring, and means comprising thermostatically controlled means for releasing the ratchet means.
